Primary Examiner—Clare E Heflin*(74) Attorney, Agent, or Firm*—Price, Heneveld, Cooper, DeWitt & Litton, LLP(57) **CLAIM**

We claim the ornamental design for a lamp housing, as shown and described.

DESCRIPTION

FIG. 1 is a top perspective view of a lamp housing showing the present invention;

FIG. 2 is a side elevation view thereof;

FIG. 3 is top plan view thereof; and,

FIG. 4 is a bottom plan view thereof.

The broken lines shown on the drawings represent environment only and form no part of the claimed design.
